PENHOLDER

Filed April 12, 1929

Inventor

Leon Hehl Ashmore:

Murray B. Boyce
Atty.

UNITED STATES PATENT OFFICE

LEON HEHL ASHMORE, OF COLLINGSWOOD, NEW JERSEY, ASSIGNOR TO THE ESTER-BROOK STEEL PEN MANUFACTURING CO., OF CAMDEN, NEW JERSEY, A CORPORATION OF NEW JERSEY

PENHOLDER

Application filed April 12, 1929. Serial No. 354,630.

My invention relates to pen holders and one object of my invention is to provide simple and efficient means for retaining a pen of any size in proper position with respect to

use, and it is very difficult to remove pen points inserted in holders of this type. The metal of most pen points is of substantially uniform thickness.

5 said holder. A further object of my invention is to provide resilient clamping means for retaining a pen in a holder.

The feature of my invention is a construction which provides for sufficient movement between the wall of the socket and an improved tip forming the subject of my invention which is mounted in such socket to permit insertion of the pen to the proper depth; such tip having a slotted portion and being so constructed and arranged as to provide for the proper positioning of the end and body of a pen point between the same and the wall of an encircling sleeve. 55

These and other features of my invention 10 are more fully described hereinafter; reference being had to the accompanying drawings, in which:

60

Figure 1 is a perspective view illustrating the parts of one form of pen holder including the features of my invention in a separated condition.

65

Figure 2 is an enlarged sectional elevation of the pen retaining end of the holder illustrated in Fig. 1; showing a pen point positioned therein.

70

Fig. 3 is a top or plan view of part of my improved pen holding means.

75

Figs. 4 and 5 are sectional plan views on the lines IV—IV, and V—V, respectively,

Fig. 2.

Figs. 6, 7 and 8 are sectional views similar to Fig. 2, illustrating modified arrangements within the scope of my invention, and

80

Fig. 9 is a sectional elevation illustrating a further modified detail within the scope of my invention.

85

The common practice in the construction of pen holders of the usual type is to provide a socket in one end of the same receiving a so-called tip, usually a tubular member, with or without a closed end; such tubular member being slotted longitudinally thereof whereby it may yield to a certain extent and permit the insertion of the pen point between the same and the wall of the socket. The slotting of such tubular portion is intended to provide for the setting up of sufficient tension to retain the pen point in position.

90

In such construction the slotting does not extend to any appreciable extent and is of such a nature and the parts are so related that a wedging action is set up immediately upon insertion of the pen point with the result that it is not easy to insert the pen point to a proper depth for the greatest convenience in

95

The wall of the tapered portion 3^b of the tip 3 may be of the same thickness as the tubular portion and the socket may extend to the lower portion of the head as indicated in Fig. 2, or it may extend substantially to the extremity of the same as illustrated in Fig. 9. The head of the tip and the tapered portion 100

thereof are slotted as indicated at 5; such slotting being preferably at right angles and providing the independently resilient finger portions 5^a clearly indicated in Figs. 3 and 4.

5 The finger portions constituting the head of the tip are preferably of material thickness, as clearly indicated in Figs. 2, 3 and 4. In Fig. 9 I have shown a tip construction slightly different from that illustrated in Fig. 2 in

10 that the socket or recess thereof is carried to a point adjacent to the end of the tip.

This arrangement is within the scope of my invention, although I prefer a tip having a head of material thickness, as illustrated

15 in Fig. 2.

This construction provides a tip of great resiliency and permits a pen point to be inserted between such tip and the socket receiving the same in any position. Such insertion

20 of a pen point sets up sufficient tension to hold the same securely in place while the tapered neck portion of the tip provides space permitting the shank of the pen point to enter the socket until the heel thereof is wedged

25 between the inner portion of the tapered neck and the wall of the socket; substantially at the point x.

By having a head provided with equally divided portions such as indicated at 5^a, the

30 clamping strain is equally distributed on the pen and there is no danger of causing pen distortion. In use, the pen point is positioned with the wall of the socket engaging one face of its body while the opposite face is engaged

35 by the head of the tip and the heel is wedged between the inner portion of the tapered neck and the inner wall of the tube 2; insuring better positioning of the pen point and holding the same in a firmer grip than may be secured with the pen holders in ordinary use.

40 At the same time the parts which hold the pen point in place by what may be termed "two-point" contact permit easy removal of a used pen point when a fresh one is to be inserted. While I have shown the slots at right

45 angles it will be understood that any form of multiple slotting that will provide substantially equal resilient portions is within the scope of my invention.

50 The construction illustrated in Figs. 1, 2, et seq., is of a type conforming to usual practice. My invention is not confined to such arrangement, however, and in Figs. 6, 7 and 8 I have illustrated other constructions and

55 arrangements or assemblies within the scope of my invention.

In Fig. 6, I have shown a tip substantially like that illustrated in Fig. 2, but which is inserted in a recess or socket 1^c formed in the

60 end of the handle. The tip shown in Fig. 6 may be hollow, or if desired it may be solid. The head and neck portion will be slotted in the same manner as the tip illustrated in Fig. 2. In this arrangement, a sleeve 2, of

65 the type illustrated in Figs. 1 and 2, may

be slipped over the tip and form with the latter the socket for the reception of a pen point.

In the construction illustrated in Fig. 7, the end of a holder, indicated at 11 may be provided with a recess 11^a receiving a tip of

70 the type illustrated in Fig. 2, or that shown in Fig. 6. In this instance the wall 11^b of the recess at the end of the handle surrounds the tip and provides with the latter the socket or space for the reception of a pen point.

75 The head and neck portion of the tip will be slotted in the same manner as the tips illustrated in Figs. 2 and 6, but the slots may be somewhat longer, as indicated at 5^b.

80 While the head of the tip may be spaced from the inner wall of this recess, as indicated in the other views, it is shown in Fig. 7 as in contact with the wall 11^b. The slotted end of the tip is sufficiently resilient to permit insertion of a pen point.

85 In the construction illustrated in Fig. 8, the slotted tip is shown as integral with the handle indicated at 111 and formed at the end of the same; such handle being of a material that will be sufficiently stiff and otherwise

90 available for the formation of a slotted tip that will perform the function of those of the inserted type. This handle will receive a sleeve 2 of the type illustrated in the other

95 views to form with the tip a socket for the reception of the pen point. The head of the tip illustrated in Fig. 8 is shown as round; differing in that respect from the head illustrated in the other views. Either form may be employed, and other contours capable of

100 performing the same function are within the scope of my invention.

As in the usual construction of pen holders of this general character, tips of the type illustrated in Figs. 1, 2 and 9 may be secured

105 to the handle by pressing up portions of the tubular wall of the same in the form of prongs 3^d, as indicated in Fig. 2.

110 My improved tip may be shaped from solid metal in any of the forms illustrated in the drawings, or rolled, drawn, spun, or otherwise formed from sheet metal, tubing, or the like.

115 While I have illustrated and described certain specific forms of construction intended to function for the desired purpose, it will be understood that I do not wish to be limited to the precise constructions illustrated nor the exact manner of associating the parts employed in developing my improved construction of pen holder, and the appended claims are intended to cover the construction illustrated as well as any modifications capable of performing the desired function.

120 I claim:

125 1. A pen holder comprising a handle, a sleeve mounted on the end of said handle, and a split tip having a plurality of independently resilient fingers fitting within said sleeve and providing with the latter a socket for the reception of a pen point; said tip

130

having a rounded head at the open end of the sleeve and a reduced neck portion below the same providing for two-point contact with an inserted pen point.

5 2. A pen holder comprising a handle having a reduced end with portions of different diameter, a tip secured to said handle, a sleeve fixedly mounted on the reduced end of said handle and enclosing the tip; said tip comprising a tubular portion which fits over the smallest end portion of the handle and snugly fits within the enclosing sleeve, a rounded head portion which extends to the end of said sleeve and is spaced from the inner wall 10 of the same and a reduced neck portion tapering from a point below said head portion to the tubular portion fitting the reduced end of the handle, with said head and neck portions diametrically slotted in two directions 15 to provide a plurality of fingers; said fingers being independently resilient for contact with the shank of a pen point inserted between said tip and sleeve with its end wedged between said parts whereby said pen point 20 has two-point contact with said tip.

3. A pen holder comprising a handle having a reduced end with a plurality of portions of different diameters; the smallest diameter being at the extreme end of the handle, a tip comprising a socketed member providing a tubular portion fitting the smaller of said reduced end portions, a sleeve surrounding said tip and fitting the larger of said reduced end portions; said tip having a 25 rounded head positioned at the end of the sleeve and a reduced neck portion tapering from a point below said head to the tubular portion thereof; the head and body of said tip being slotted to provide a plurality of independently resilient finger portions for engagement with a pen nib inserted between 30 the same and the enclosing sleeve.

4. A tip for pen holder handles having a plurality of reduced end portions, in combination with a sleeve at the end of the handle; said tip comprising a socketed member providing a tubular portion fitting one portion of the reduced end of the holder, a rounded head positioned at the open end of 45 said sleeve and a reduced neck portion below said head; said socketed portion terminating short of the lower end of the head and the latter with the neck portion being diametrically slotted in a plurality of directions; said tip 50 slots extending a considerable distance below the head whereby the segmental portions of said tip produced by such slotting are independently resilient.

In witness whereof I have signed this 55 specification.

LEON H. ASHMORE.
